UNITED STATES PATENT OFFICE.

JAMES W. SUPORTER AND HENRY G. DIBELKA, OF CHICAGO, ILLINOIS, ASSIGNEES TO
MILLER & PARDEE, INC., OF CHICAGO, ILLINOIS, A CORPORATION OF ILLINOIS.

DESIGN FOR A RADIATOR CAP.

Application filed March 6, 1922. Serial No. 1,060 1/2. Term of patent 14 years.

To all whom it may concern:

Be it known that we, JAMES W. SUPORTER and HENRY G. DIBELKA, both citizens of the United States, and both residing in Chicago, Cook County, Illinois, have invented a new, original, and ornamental Design for Radiator Caps, of which the following is a specification, reference being had to the accompanying drawing, forming part hereof, in which—

Fig. 1 is a front elevation;
Fig. 2 is a left side elevation.

We claim:

The ornamental design for a radiator cap substantially as shown.

In testimony whereof we have signed our names to this specification this 27th day of January, 1922.

JAMES W. SUPORTER.
HENRY G. DIBELKA.
